(57) **ABSTRACT**

A striking tool is disclosed that comprises a generally U-shaped or V-shaped handle constructed of a substantially resilient material and having a head fixed at one end thereof. A second end of the handle has a hand grip or gripping region adapted to be grasped by a human hand. The second end of the U-shaped or V-shaped handle includes a flange, or stop member, to inhibit the handle from slipping out of the grasping hand. The hand grip may include a lip at a lower end thereof, such that a pinky finger of the hand may be comfortably placed on either side of the lip while the hand grasps the hand grip. The resilient material construction of the handle permits a first end of the handle to flex slightly towards and away from the second end of the handle. Accordingly, during use, the striking tool provides a damped recoil and improved striking action, imparting less shock to the hand, wrist, elbow, shoulder, and other parts of the body, as compared to a conventional striking tool.

HAMMER HAVING SHOCK ABSORBING
HANDLECROSS-REFERENCE TO RELATED
APPLICATIONS

This application claims the benefit of U.S. provisional application No. 60/943,265, filed on Jun. 11, 2007, the entirety of which is hereby incorporated by reference.

BACKGROUND OF THE INVENTION

1. Field of the Invention

This invention relates generally to hand tools, and more particularly to striking tools such as hammers.

2. Description of Related Art

Hammers and other hand tools with bent handles are known in the art. For example, U.S. Pat. No. 4,154,273 and U.S. Pat. No. 4,958,540 each teach such a device, as does Canadian Patent No. 2,208,951. Such handles may potentially provide improved control of a hammer in certain situations, and may potentially provide some strain relief to the wrist. However, none of these patents discloses a striking tool including a spring-action handle that would assist in absorbing some of the impact shock imparted to the user's hand, wrist, elbow, shoulder, and other portions of the body upon striking a nail, for example, and would assist in returning the hammer to its original starting position above the nail.

Accordingly, it is an object of the present invention to provide a striking tool having a spring-action type handle that can dampen some of the impact shock experienced by a user's hand, wrist, elbow, shoulder, and other portions of the body upon striking an object.

It is also an object of the present invention to provide a striking tool that can assist in returning the tool to its original starting point above the position of a struck object through a spring force generated within its handle.

It is yet another object of the present invention to provide a striking tool having improved user ergonomics.

It is still another object of the present invention to provide a striking tool having a handle configuration facilitating increased use of the shoulder and elbow joints, back muscles and body weight in the striking motion, with reduced movement of the wrist and, accordingly, potentially reduced wrist strain.

These and other objects and features of the present invention will become apparent in view of the present specification, drawings and claims.

BRIEF SUMMARY OF THE INVENTION

A hand-held striking tool is provided. The tool comprises a head having a striking surface, and a handle affixed to the head. The handle is constructed of a substantially resilient material and has a first end proximate the head, a second end, and at least one discontinuous region positioned between the first end and the second end.

In a preferred embodiment, the at least one discontinuous region provides a spring action between the first end and the second end upon striking an object with the striking surface of the head. Moreover, in a preferred embodiment, the striking tool comprises a hammer, and the head comprises a hammer head.

The at least one discontinuous region may comprise, for example, at least one bend which, in a preferred embodiment,

2

comprises at least one curved region. The at least one curved region may be, for example, substantially U-shaped or substantially V-shaped.

The handle may further include a grasping region. A hand grip may be disposed proximate the grasping region. In one embodiment of the invention, at least a portion of the hand grip comprises a separate component, at least a portion of which is attached to the handle. In another embodiment of the invention, at least a portion of the hand grip is integrally formed with the handle.

Moreover, the hand grip may further include at least one finger accepting indentation. The hand grip may further include at least one lip. Furthermore, the handle may further include a stop member proximate the second end.

In an embodiment of the present invention, the handle further includes a first elongated region having a first longitudinal axis and a second elongated region having a second longitudinal axis. In this embodiment, the first longitudinal axis is nonparallel to the second longitudinal axis. In particular, in this embodiment, the first longitudinal axis and the second longitudinal axis are inclined relative to each other. This angle of inclination may be, for example, an acute angle. Moreover, in one embodiment, this acute angle may be approximately seven degrees. In another embodiment, this acute angle may be approximately ten degrees.

The handle may be constructed of fiberglass, carbon fiber, fiberglass reinforced plastic, carbon fiber reinforced plastic, a synthetic fiber, Kevlar®, spring steel, tubular aluminum, tubular steel, a phenolic material, laminated wood, or a laminated synthetic material, including materials in strip form.

BRIEF DESCRIPTION OF THE SEVERAL
VIEWS OF THE DRAWINGS

35 FIG. 1 is a side elevational view of a first embodiment of the present invention and showing, in particular, the relative flexing of certain regions of the handle;

FIG. 2 is a side elevational view of the first embodiment of the present invention and, showing, in particular, a human hand gripping a portion of the handle in a first orientation;

FIG. 3 is a side elevational view of the first embodiment of the present invention and, showing, in particular, a human hand gripping a portion of the handle in a second orientation;

FIG. 4 is a perspective view of a second embodiment of the present invention;

FIG. 5 is a sectional view of the second embodiment of the present invention, taken generally along line 5-5 of FIG. 4 and looking in the direction of the arrows;

FIG. 6 is a side elevational view of one embodiment of the central core;

FIG. 7 is a sectional view of the embodiment of the sectional core of FIG. 6, taken generally along line 7-7 of FIG. 6 and looking in the direction of the arrows;

FIG. 8 is a side elevational view of a third embodiment of the present invention;

FIG. 9 is a side elevational view of a fourth embodiment of the present invention;

FIG. 10 is a side elevational view of a fifth embodiment of the present invention; and

FIG. 11 is a side elevational view of a sixth embodiment of the present invention.

DETAILED DESCRIPTION OF THE INVENTION

65 While the present invention may be embodied in many different forms, there is shown in the drawings and will herein be described in detail, several specific embodiments, with the

understanding that the pre disclosure can be considered as an exemplification of the principles of the present invention and is not intended to limit the present invention to the embodiments illustrated.

While several different embodiments of the present invention are described herein and shown in the various figures, common reference numerals in the figures denote similar or analogous elements or structure amongst the various embodiments.

A first embodiment of the present hammer **10** is shown in FIGS. 1-3 as comprising handle **20**, having first end **34** affixed to hammer head **30**. Handle **20** includes first substantially linear region **31**, second substantially linear region **32**, and bottom curved region **35**, interposed between first linear region **31** and second linear region **32**. Second linear region **32** includes gripping region **40**. A hand grip **50** is disposed about a portion of linear region **32** at gripping region **40**. Hand grip **50** includes finger accepting indentations **51** and lip **70** proximate lower end **54** of hand grip **50**. A flange, or protrusion **60**, is disposed at second end **36** of handle **20**.

As shown in FIG. 1, an optional central core **80** may be disposed within handle **20**. Central core **80**, when present, provides additional strength and reinforcement to handle **20**. Central core **80** is preferably constructed of a suitable high strength yet resilient material.

Hammer head **30** may be, for example, a conventional claw hammer head, having a striking end and a claw end. Moreover, hammer heads of alternative shape and construction, such as, for example, engineer's hammer heads, drilling hammer heads, framing hammer heads, geologist's hammer heads, upholstery hammer heads, cross-peen hammer heads, ball-peen hammer heads, sledgehammer heads, mallet heads, and the heads of other striking tools, such as hand axes and hatchets, are likewise contemplated by the present invention.

Gripping region **40** and hand grip **50**, including finger accepting indentations **51**, facilitate the grasping of hammer **10** by a human hand **15**, as shown in FIGS. 2 and 3. Lip **70** of hand grip **50** permits pinkie finger **18** of hand **15** to be comfortably placed either above lip **70**, as shown in FIG. 2, or below lip **70**, as shown in FIG. 3, as hand **15** grasps hand grip **50** and, in turn, gripping region **40** of substantially linear region **32** of handle **20**. Accordingly, a user can grasp hammer **10** with either type of grip, as desired for comfort and control. Hand grip **50** may be constructed, for example, of an elastomeric rubber or rubberized material, a foam material, an over-molded plastic material, or other comfortable material providing a secure grasping surface. Alternatively, hand grip **50** may be integrally formed with handle **20**, and may include integrally formed finger accepting indentations **51** and/or knurling, or other integrally formed grip-enhancing raised areas and indentations, proximate gripping region **40**.

Protrusion **60** may optionally be included to serve as a stop member, to inhibit any inadvertent slippage of handle **20** out of the user's grasping hand. Protrusion **60** may alternately be incorporated into the hand grip **50**, such as in the form of an enlarged lip or flange proximate the upper end of hand grip **50**, or may be releasably attachable to, rather than integrally formed with, handle **20**.

Handle **20** is preferably constructed of a substantially resilient material, permitting first end **34** of the handle **20** to flex slightly towards and away from second end **36**, facilitated by the flexing of handle **20**, specifically, proximate bottom curved region **35**. In FIG. 1, hammer head **30** and first linear region **31** of handle **20** are shown in solid lines to depict handle **20** being flexed, in its partially compressed configu-

ration. Hammer head **30** and first linear region **31** of handle **20** are shown in phantom lines in FIG. 1 to depict handle **20** in its uncompressed configuration.

Handle **20** may be constructed, for example, of one or more of a variety of resilient materials, including composite fiberglass, carbon fiber, fiberglass reinforced plastic, carbon fiber reinforced plastic, synthetic fibers such as Kevlar®, other fiber or fiber-reinforced materials, spring steel, tubular aluminum, steel, or other elemental metal or alloy in tubular form, a phenolic material, laminated wood, a laminated synthetic material, or other such suitably strong yet resilient materials or combinations thereof, including materials in strip form. For example, a plurality of layers of woven fiberglass, in combination with chopped fiberglass, may be bound together with an epoxy resin, and cured under pressure, with vacuum used to extract any air bubbles during manufacture of the handle. A gelcoat material may optionally be applied to handle **20** to provide a quality surface finish. Moreover, for fiberglass embodiments of handle **20**, specialized methods of fiberglass manufacture, such as a sheet molding compound, a resin transfer molding technique, or a variant of a Pultrusion or other continuous composite material manufacturing technique, may alternatively be employed.

Due to the use of resilient materials, and the nonstandard shape and configuration of the handles of the various embodiments of the present invention, during use, hammer **10** has an improved, spring-like striking and recoil action, imparting less shock to the hand **15**, wrist, elbow, shoulder, and other portions of the body than conventional hammers and aiding in the return of the hammer to an original upraised position. Hammer **10** is accordingly easier to use than a conventional hammer since the spring-action of handle **20** helps push the hammer back above a nail that is being driven into wood, for example.

Moreover, in this embodiment of the invention, and as shown in FIGS. 1-3, the longitudinal axes of first linear region **31** and second linear region **32** of handle **20** are not substantially aligned. Rather, they are inclined away from each other at an acute angle of, for example, approximately seven degrees. Bottom curved region **35** accordingly describes an arc of approximately one hundred seventy-three degrees (i.e., one hundred eighty degrees less the relative inclination of seven degrees). In another embodiment of the present invention, this acute angle is approximately ten degrees, and bottom curved region **35** accordingly describes an arc of approximately one hundred seventy degrees. This relative inclination, in combination with the distal spacing of first linear region **31** and second linear region **32**, results in improved ergonomics of use for many users. In particular, this configuration tends to require relatively less wrist flexion when striking a nail or other target with hammer **10**, as compared with conventional hammers. Rather, increased use is made of the elbow and shoulder joints, as well as the back muscles and other parts of the body, as hammer **10** is swung in a striking motion. As the shoulder and elbow tend to be stronger and more powerful joints than the wrist, many users may experience an improved and more naturally feeling swinging motion of hammer **10**, as compared with conventional hammers. Moreover, the increased distance from hammer head **30** created by the offset of second linear region **32** results in a longer lever arm and an increased moment at the hammer head, providing a smoother, pendulum-like swing with an increased striking force. Other angles, or a parallel relationship between first linear region **31** and second linear region **32**, may alternatively be employed. When a parallel relationship is employed, the distal spacing between first linear region **31** and second linear region **32** still provides

5

significant ergonomic improvement, relative to conventional hammers, including reduced wrist flexion

A second embodiment of the present hammer **10** is shown in FIGS. 4-5. In this embodiment, first linear region **31** and second linear region **32** are again inclined away from each other at a relative acute angle of approximately seven degrees or, in an alternative embodiment, approximately ten degrees. Moreover, in this embodiment, hand grip **50** is eliminated, with the user grasping the handle surface directly at gripping region **40** of handle **20**. The function of lip **70** of grip means **50** of FIGS. 1-3 is instead provided by integrally formed protrusions **70'** and **70"** on opposing sides of second linear region **32**, proximate its juncture with bottom curved region **35** of handle **20**. Of course, a separate hand grip, such as a hand grip rubber or rubberized material that may be substantially flush with surrounding regions of the handle, may alternatively be used. As best seen in FIG. 4, while both protrusion **70'** and **70"** have a curved apex, protrusion **70'**, disposed inwardly towards first linear region **31** of handle **20**, is significantly larger in size than protrusion **70"**, disposed outwardly, away from first linear region **31**. As best seen in FIG. 5, in this embodiment, central core **80** may be, for example, cylindrical in shape and circular in cross section or, as will be described supra, may have other configurations, such as elliptical or stadium in cross-section.

In this second embodiment of the present invention, bottom curved region **35** has an inner radius of approximately 0.500 inches, and an outer radius of curvature of approximately 1.750 inches, relative to center of curvature **84**. First linear region **31** has a length of approximately 12.000 inches, extending from transverse line **90** intersecting center of curvature **84**, to the lower surface of hammer head **30**. Additional length of first linear region **31** extends within an aperture of hammer head **30** and facilitates the securing hammer head **30** and handle **20** together. Second linear region **32** has a length of approximately 7.500 inches, extending from transverse line **90** to an apex of protrusion, or stop member **60**. Handle **20** has a maximum width along its overall length of approximately 1.125 inches.

An alternative construction of central core **80** is shown in FIGS. 6-7 as comprising first substantially linear region **81**, second substantially linear region **82**, and bottom curved region **83**, interposed between first linear region **81** and second linear region **82**. In one embodiment of the present invention, bottom curved region **83** has an inner radius **85** of approximately 0.750 inches, and an outer radius **86** of approximately 1.650 inches, relative to center of curvature **84**. First linear region **81** has a length of approximately 13.750 inches, extending from transverse line **90** intersecting center of curvature **84**, to an opposing endpoint (not shown). Second linear region **82** has a length of approximately 6.400 inches, extending from transverse line **90** to opposing endpoint **91**. Moreover, in this embodiment, the longitudinal axes of first linear region **81** and second linear region **82** of central core **80** are not substantially aligned. Rather, they are inclined away from each other at an acute angle **87**. In one embodiment of the present invention, angle **87** is approximately seven degrees. In another embodiment of the invention, angle **87** is approximately ten degrees. Other angles, or a parallel relationship between first linear region **81** and second linear region **82** may alternatively be used, as dictated by the desired angle of the first and second linear regions of the handle in which central core **80** is to be embedded.

As shown in FIG. 7, in this embodiment, central core **80** has a cross-section that is substantially stadium shaped, rather than the circular cross-section of the embodiment of FIGS. 4-5. In particular, central core **80**, in cross-section, includes

6

two opposing linear sides **88**, joined by opposing curved ends **89**. Central core **80** has a cross-sectional length of approximately 0.900 inches and a cross sectional width of approximately 0.500 inches. Moreover, opposing linear sides **88** each have a radius of curvature of approximately 0.250 inches.

Another alternative embodiment of hammer **10** is shown in FIG. 8. In this embodiment, first curved region **37**, third substantially linear region **33**, and second curved region **38** are interposed between first substantially linear region **31** and second substantially linear region **32**. Moreover, in this embodiment, second linear portion **32** extends further below first linear portion **31**, relative to hammer head **30**, rather than extending back vertically towards hammer head **30**. Furthermore, in this embodiment, the longitudinal axes of first linear region **31** and second linear region **32** are substantially parallel to each other. In addition, in this embodiment, second end **36** of handle **20** terminates in a flared region **61**, inhibiting handle **20** from slipping out of the user's hand while in use. As in the previously discussed embodiments, handle **20** is constructed of a resilient material which, in combination with the nonlinear hammer configuration and offset between first linear region **31** and second linear region **32**, enable the handle to both perform a shock absorbing function and to provide improved user ergonomics.

Yet another alternative embodiment of hammer **10** is shown in FIG. 9. This embodiment is similar in overall configuration to the embodiment of FIG. 8, with the exception that at least one of first curved region **37** and second curved region **38** have a different angle of curvature, resulting in the longitudinal axes of first linear portion **31** and second linear portion **32** being nonparallel to each other. In particular, from the perspective of a user grasping handle **20** proximate gripping region **40**, first linear region **31** angles and extends away from the user. As in the previously discussed embodiments, handle **10** is constructed of a resilient material which, in combination with the nonlinear hammer configuration and offset between first linear region **31** and second linear region **32**, enable the handle to both perform a shock absorbing function and to provide improved user ergonomics.

Still another embodiment of hammer **10** is shown in FIG. 10. In this embodiment, first linear portion **31** and second linear portion **32** have longitudinal axes that are substantially collinear. Moreover, in this embodiment, a plurality of opposing curved regions **39** are interposed between first linear portion **31** and second linear portion **32**. As in the previously discussed embodiments, handle **10** is constructed of a resilient material which, in combination with the wave-like or oscillating configuration created by curved regions **39**, enables the handle to perform a spring-like, shock absorbing function. Although five curved regions **39** are shown in FIG. 10, fewer or additional curved regions may alternatively be employed.

A further embodiment of hammer **10** is shown in FIG. 11. In this embodiment, first linear portion **31** and second linear portion **32** have longitudinal axes that are substantially collinear. Moreover, in this embodiment, a coiled or looped region **90** is interposed between first linear portion **31** and second linear portion **32**. As in the previously discussed embodiments, handle **10** is constructed of a resilient material which in combination with the coil-like configuration created by looped region **90**, enables the handle to perform a spring-like, shock absorbing function. Although a single looped region **90** is shown in FIG. 11, a plurality of such looped regions may alternatively be employed.

The foregoing description and drawings are merely to explain and illustrate the invention, and the invention is not limited thereto except insofar as the following claims are so

limited, as those skilled in the art with the present disclosure before them will be able to make modifications and variations therein without departing from the scope of the invention.

What is claimed is:

1. A hand-held striking tool comprising:
a head having a striking surface; and
a handle coupled to the head, the handle being constructed of a substantially resilient material and having a first end proximate the head, a free second end, and at least one discontinuous region positioned between the first end and the free second end, the at least one discontinuous region providing a spring action upon striking an object with the striking surface of the head,
said at least one discontinuous region being divided into two elongated non-parallel regions separated by a curved region, wherein the curved region is substantially U-shaped, said two elongated regions extending at an acute angle with respect to each other, one of the two elongated regions having a central longitudinal axis centrally extending along the one elongated region terminating in the head, the other of the two elongated regions terminating in the free second end, the free second end being located between the first end and the curved region relative to said central longitudinal axis while being spaced from the one elongated region, the striking surface of the head being on one side of the central longitudinal axis and the other of the two elongated regions being on an opposite side of the central longitudinal axis,

the other elongated region defining a hand grip portion of the handle within a grasping region.

2. The invention according to claim 1, wherein the striking tool comprises a hammer, and the head comprises a hammer head.
3. The invention according to claim 1, wherein at least a portion of the hand grip comprises a separate component, at least a portion of which is attached to the handle.
4. The invention according to claim 1, wherein at least a portion of the hand grip is integrally formed with the handle.
5. The invention according to claim 1, wherein the hand grip includes at least one finger accepting indentation.
6. The invention according to claim 1, wherein the hand grip includes at least one lip.
7. The invention according to claim 1, wherein the handle further includes a stop member proximate the second end.
8. The invention according to claim 1, wherein the acute angle is an angle of approximately seven degrees.
9. The invention according to claim 1, wherein the acute angle is an angle of approximately ten degrees.
10. The invention according to claim 1, wherein the handle is constructed of at least one material selected from the group comprising fiberglass, carbon fiber, fiberglass reinforced plastic, carbon fiber reinforced plastic, a synthetic fiber, spring steel, tubular aluminum, tubular steel, a phenolic material, laminated wood, or a laminated synthetic material.

* * * * *
